US00D879437S

(12) **United States Design Patent** (10) Patent No.: **US D879,437 S**
(45) Date of Patent: **** Mar. 31, 2020**

(54) **SHOE**

(71) Applicant: **Reebok International Limited**, London (GB)
(72) Inventors: **Marc V. Brosseau**, Boston, MA (US); **Dustin Simone**, Boston, MA (US)
(73) Assignee: **Reebok International Limited**, London (GB)

(**) Term: **15 Years**

(21) Appl. No.: **29/659,478**

(22) Filed: **Aug. 9, 2018**

(51) LOC (12) Cl. **02-04**
(52) U.S. Cl.
USPC **D2/959**; D2/947; D2/951; D2/953;

CLAIM

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the shoe that form no part of the claimed design.

1 Claim, 6 Drawing Sheets
